OTHER PUBLICATIONS“Apollo GUI Set” Sep. 7, 2012 <http://www.coolwebmasters.com/best-of-the-web/3134-apollo-psd-gui.html>.*Primary Examiner* — Melanie H Tung*Assistant Examiner* — Bao-Yen T Nguyen(74) *Attorney, Agent, or Firm* — Caitlyn Ross**CLAIM**

The ornamental design for a display screen with graphical user interface, as shown and described.

DESCRIPTION

FIG. 1 is a front view of a first embodiment of a graphical user interface for a display screen, showing our new design; and,

FIG. 2 is a front view of a second embodiment of the graphical user interface for a display screen, showing our new design.

The broken lines showing a display screen form no part of the claimed design. The broken lines show portions of the graphical user interface that form no part of the claimed design.
